FOLDING MECHANISM

Curtis S. Crafts, Oak Park, Ill., assignor to Goss
Printing Press Company, a corporation of
Illinois

Application October 23, 1929, Serial No. 401,677
Renewed October 31, 1931

34 Claims. (Cl. 270—77)

This invention relates to a new and useful folding mechanism and more particularly to a transverse folding mechanism for use in connection with high speed rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Figure 1 is a side elevation of a folding mechanism illustrating one embodiment of the present invention, certain parts being broken away.

Figure 2 is an end view looking from the right of 25 Figure 1, with certain parts broken away.

Figure 3 is a fragmentary horizontal section taken on the line 3—3 of Figure 1.

Figure 4 is a fragmentary detailed view showing the gearing for driving the folding rollers.

30 Figure 5 is a fragmentary detailed section taken on the line 5—5 of Figure 3.

The invention is directed primarily to a mechanism for quickly and instantaneously retracting a folding roller to permit easy and immediate removal from the folding roller of a choked paper, and then quickly and easily restoring the roller to its folding position with respect to its cooperating roller. It sometimes happens, especially in rapid newspaper folding wherein heavy newspapers are given the final transverse fold at the rate of thirty-five thousand to forty thousand folds per hour, that a paper will become jammed or choked in the folding rollers, and it is exceedingly desirable to be able to immediately and with very little trouble clean out a choked or jammed paper and have the folding roller returned easily, immediately and accurately to folding position.

The invention is directed further to providing 50 functions and capacities as just described in connection with mechanism for variably and accurately positioning both folding rollers to regulate the width of opening between them as well as their distance from the folding cylinder. Such variable positioning is necessary in presses 55 wherein the number of pages in successive issues

varies very widely, the range of variance frequently being, for example, between eight pages and sixty-four pages or more for different issues or days, and for effective folding it is necessary that the space between the two cooperating folding rollers be correspondingly varied and regulated as well as the distance from the folding cylinder to prevent circling off of the outside sheets as their heads pass the second folding roller.

5 The invention provides a folding mechanism adapted for use with high speed rotary printing presses and is particularly useful in the production of relatively thick folded products. The present invention also provides a folding mechanism having means for adjustably moving the folding rollers away from each other and preferably away from the folding cylinder. Means are also provided for quickly moving either of the folding rollers out of folding relation with the other and away from the cylinder to release a 10 choked fold, and preferably the rollers are so mounted that they can be returned to their original adjusted position without necessitating a readjustment. Preferably, and as embodied, the folding rollers are resiliently urged towards each other and are mounted in arms movable about a common axis external to the folding cylinder, the arms being provided with means for simultaneously moving them away from the line of fold.

15 The invention, as embodied, is also applied to a folding mechanism embodying the foregoing described features and constructions and wherein both folding rollers have a resilient action when in folding position and during the folding operation.

20 The invention is shown applied to a fast rotary transverse newspaper folder, and the invention finds one of its greatest fields of usefulness in such machines, although it will be understood that it is applicable to, and useful with, other kinds of folding mechanisms.

25 Referring now in detail to the embodiment of the invention illustrated by way of example in the accompanying drawings, the general frame of a printing press is indicated by 1, and a folding cylinder by 2. The cylinder may be of any usual or known form, and has its shaft 3 mounted in bearings 4 carried upon the cross reaches 5 of the folder side frames of press.

30 The cooperating mechanism for cutting the web and engaging and carrying the new web end is shown only partially and in a general way, and may be of standard or other convenient form. The successive head ends of the webs are held by either of two sets of semi-circumferentially

separated impaling pins, the pins being forced through the lead end of the plicated webs when the transverse cut is made in the usual manner. The transverse series of impaling pins are mounted in the corresponding cutting blocks 11, with which cooperate the cutting blades. The blades are mounted on the cylinder 13, the shaft 14 of which is journaled in bearings 15 carried on the reaches 5 of the side frames of the folder.

10   Mounted on the folding cylinder 2 are two tucking blade mechanisms 22 and 23, respectively, located a semi-circumference apart, these blades being preferably of the usual double type. The shafts of the blades 24 and 25, respectively, 15 are journaled in the cylinder 2, and fixed centrally to these respective shafts are corresponding actuating arms 26 and 27. The arm 26 has at either end thereof cam rollers 28 and 29, and the arm 27 has at the ends thereof corresponding cam rollers 30 and 31. These cooperate with suitable actuating mechanisms (not shown), which may be of any standard or suitable form, such as the well known Husby cam mechanism. All the foregoing mechanism is old and well known and may be of any standard form or any other suitable form, as may be desired.

Referring now in detail to the folding rollers between which the newspapers, or other group of sheets, is tucked by the folding blade 22 or 23, the folding rollers 35 and 36 are rotatably journaled directly beneath the shaft 3 of the folding cylinder 2 and parallel with said shaft. Means are provided for moving the folding rollers toward and away from each other and toward and away from the folding cylinder and preferably are movable around an axis external to the folding cylinder. As embodied, the folding rollers 35 and 36 are each rotatably journaled at one end by means of bearings 37 and 38 respectively formed at the upper portion of arms 40 and 41 respectively, and are similarly journaled at their other end by means of bearings formed at the upper ends of similar arms 42 and 43. Arms 40, 41, 42, 43 are pivotally mounted on stub shafts 44 and 45, inwardly extending from the press frame 1 and supported at their inner end by means of brackets 46 and 47 attached to the press frame.

50   The folding rollers 35 and 36 are preferably resiliently urged toward each other to cause the roller to resiliently grip the group of folded sheets as it is tucked into the bite of the folding rollers by folding blade 22 or 23. As embodied, the upper ends of arms 40, 41, 42 and 43 are provided 55 with lugs 50 at their outer side, with which are pivotally connected plungers 51 slidably mounted in housings 52 connected with and supported by the press frame 1 as will be more fully described. Plungers 51 are provided with a reduced portion 53 around which is coiled a compression spring 54 compressed between the plunger 51 and the end wall 55 of the housing 52, as shown in Fig. 5.

Referring now to the means for variably and 60 regularly simultaneously positioning the folding rollers 35 and 36 to move them toward and from each other and the folding cylinder 2, folding roller supporting arms 40, 41, 42 and 43 are pivotally mounted on shafts 44 and 45 and are provided at their lower parts with downwardly extending offset arms 60, 61, 62 and 63 respectively. The downwardly extending pairs of arms 60, 61 and 62, 63 are preferably bent toward each other and provided with forked ends forming aligned slots 64 and 65 to receive adjusting rods 66 and 75 67 rotatably supported in an aperture in brackets

46 and 47 respectively. At either side of bracket 46, the shaft 66 is provided with oppositely threaded portions 68, 69 cooperating with threaded collars 70 and 71 positioned between the bracket 46 and depending arms 60 and 61 respectively. As shaft 66 is rotated, collars 70 and 71 and arms 40 and 41 are simultaneously moved toward and from each other to vary the distance between the folding rollers 35 and 36.

At the other end of folding rollers 35 and 36 10 is provided similar mechanism for simultaneously moving arms 42 and 43 and as embodied, shaft 73 is rotatably mounted in bracket 47 and provided with oppositely threaded collars 74 (only one being shown) engaging the depending portion of 15 arms 62 and 63.

Means are preferably provided for simultaneously moving each end of the folding rollers 35 and 36, while maintaining them parallel as they are moved toward and from each other, and, as 20 embodied, shafts 66 and 67 are provided with bevel gears 75 and 76 respectively, meshing with bevel gears 77 and 78 on shaft 79 extending transversely of the frame 1. A handwheel 80 is mounted on shaft 79 externally of the press frame, 25 and permits ready adjustment of the folding rollers 35 and 36.

Means are also provided for quickly moving the folding rollers away from each other and the folding cylinder and to non-folding position with 30 respect to each other, and as embodied, the outer ends of the spring housings 52 are pivotally mounted by means of pivot pins 82 on arms 83 rigidly secured on shafts 84 extending transversely of the frame 1. Shafts 84 are rotatably journaled in the frame and each is provided at one 35 end with a hand lever 85 by which the corresponding shaft 84 and arm 83 may be moved to vary the position of the folding rollers 35 and 36. One shaft 84 is provided for each of the folding rollers 40 and the ends of the folding rollers are connected with the arms 83 on shaft 84 by means of the spring housings 52.

For holding the folding rollers in folding relation with each other and the folding cylinder, 45 hand levers 85 are provided with pins 86 to engage corresponding depressions in the press frame 1, and these pins 86 are urged into their corresponding depression by means of springs 87 pressing against the head of pins 86 and retained with 50 in a suitable hole in the hand lever by means of screws 88.

Means are provided for limiting the movement of arms 84 to which the spring housings are pivotally mounted permitting the folding rollers to 55 be returned to their original adjusted position after having been moved apart to release a choked fold, thereby avoiding any necessity for a readjustment of the gap between the folding rollers. Preferably the outer ends of the spring housings 60 52, connected with the arms 83, are formed with depending shoes 90 adapted to contact with a corresponding flat surface 91 formed on arm 83 and adjacent to pivot pin 82. If desired, these flat surfaces may be so formed that they contact only 65 after the pivot pin has been moved slightly above the line passing through the center of shaft 84 and the pivot of plunger 51, thereby forming a toggle which will normally hold the folding rollers against movement away from each other, except as they move against the compression of springs 54.

Means are also provided in the present embodiment for driving the folding rollers in any of their adjusted positions, and preferably for driv- 75

ing them from the folding cylinder. As embodied, a gear 95 is rigidly mounted on the folding cylinder shaft 3, and meshes with an idler 96 rotatably journaled on stub shaft 97 mounted externally of the frame 1, the idler in turn meshing with a pinion 98 rotatably journaled in the frame by shaft 99 which is rotatably supported at its outer end by bracket 100, attached to the outside of the press frame 1. At its inner end, shaft 99 carries a relatively wide pinion 101, fixed thereon, meshing with a gear 102 at the end of the shaft of folding roller 36 and fast therewith, and also meshing with idler 103, rotatably mounted on the inside of the press frame, which in turn meshes with gear 104 mounted on the end of the shaft of folding roller 35. Gears 102 and 104 are preferably offset with respect to each other in order that they may move radially to and from each other without interference as the folding rollers are adjusted. Preferably, and as embodied, gear 101 is mounted substantially directly beneath gear 102, and idler 103 is mounted substantially directly beneath gear 104, and as the folding rollers are moved away from each other, gears 101 and 104 remain in mesh with their driving gears over a relatively large range of adjustment. As shown in the drawings, the folding roller driving gears will remain in mesh with their driving gears in any normal folding adjustment of the folding rollers, and at the same time free folding roller driving gears 102 and 104 when the folding rollers are moved to choke releasing position, thereby facilitating the removal of the paper from between the rollers.

35. Folding rollers 35 and 36 and their driving gears are preferably so proportioned that the peripheral speed of the folding rollers is very slightly in excess of that of the folding cylinder, although, of course, these parts may be so proportioned that the peripheral speed of the folding rollers and cylinder is the same.

The invention in its broader aspects is not limited to the specific mechanisms shown and described but departures may be made therefrom within the scope of the accompanying claims without departing from the principles of the invention and without sacrificing its chief advantages.

What I claim is:—

50. 1. In a printing press folder, the combination with the folding cylinder and its blade, of a pair of folding rollers mounted for movement around a pivot outside the circumference of the folding cylinder and means for moving the rollers to and from each other and the cylinder.

55. 2. In a printing press folder, the combination with the folding cylinder and its blade, of a pair of folding rollers mounted in arms movable about a common axis external to the folding cylinder, means for variably positioning said rollers relative to each other and means for quickly moving said rollers out of folding relation.

60. 3. In a printing press folder, the combination with the folding cylinder and its blade, of a pair of folding rollers mounted in arms movable about a common axis external to the folding cylinder, means for yieldingly urging said rollers together and means for spacing said rollers from each other.

65. 4. In a printing press folder, the combination with the folding cylinder and its blade, of a pair of folding rollers, means for variably spacing them from each other, means for yieldingly urging them together and a toggle connected to each roller for quickly releasing the folding rollers.

5. In a printing press folder, the combination with the folding cylinder and its blade, of a pair of folding rollers, and toggle mechanism for holding said rollers in folding relation.

10. 6. In a printing press folder, the combination with the folding cylinder and its blade, of a pair of folding rollers, toggle mechanism for holding said rollers in folding relation and means for moving either folding roller out of folding relation to the cylinder.

15. 7. In a printing press folder, the combination with the folding cylinder and its blade, of a pair of folding rollers, toggle mechanism including yielding connections with the folding rollers for yieldingly holding said rollers in folding relation and means for moving either folding roller out of folding relation to the cylinder.

20. 8. In a printing press folder, the combination with the folding cylinder and its blade, of a pair of folding rollers mounted for movement around a pivot beyond the circumference of the folding cylinder and means for moving the rollers to and from each other.

25. 9. In a printing press folder, the combination with the folding cylinder and its blade, of a pair of folding rollers and means positioned beyond the circumference of the cylinder for pivotally and yieldingly mounting said rollers.

30. 10. In a printing press folder, the combination with the folding cylinder and its blade, of a pair of folding rollers, and toggle mechanism yieldingly pressing said rollers together.

35. 11. In a printing press folder, the combination with the folding cylinder and its blade, of a pair of folding rollers, toggle mechanism yieldingly connected to said rollers and pressing them together and means for breaking the toggles to open the rollers and release chokes.

40. 12. In a printing press folder, the combination with the folding cylinder and its blade, of a pair of folding rollers, toggle mechanism yieldingly connected to said rollers and pressing them together, means for minutely and variably spacing said rollers and means for breaking the toggles to quickly release a choke.

45. 13. In a printing press folder, the combination with the folding cylinder and its blade, of a pair of folding rollers, a toggle mechanism yieldingly connected to each of said rollers and pressing them together, means for minutely varying the spacing of the rollers, and means for breaking either of the toggles to quickly release a choke.

50. 14. In a printing press folder, the combination with the folding cylinder and its blade, of a pair of folding rollers pivotally mounted externally of the cylinder, and toggle mechanism yieldingly pressing said rollers together.

55. 15. In a printing press folder, the combination with the folding cylinder and its blade, of a pair of folding rollers pivotally mounted externally of the cylinder, toggle mechanism yieldingly connected to said rollers and pressing them together and means for breaking the toggles to open the rollers and release chokes.

60. 16. In a printing press folder, the combination with the folding cylinder and its blade, of a pair of folding rollers pivotally mounted externally of the cylinder, toggle mechanism yieldingly connected to said rollers and pressing them together, means for minutely and variably spacing said rollers and means for breaking the toggles to quickly release a choke.

65. 17. In a printing press folder, the combination with the folding cylinder and its blade, of a pair of folding rollers, toggle mechanism yieldingly

- connected to said rollers and pressing them together, means for minutely and variably spacing said rollers while maintaining them equidistant from the folding point and means for breaking the toggles to quickly release a choke. 5
18. In a printing press folder, the combination with the folding cylinder and its blade, of a pair of folding rollers, a toggle mechanism yieldingly connected to each of said rollers and pressing them together, means for minutely varying the spacing of the rollers while maintaining them equidistant from the folding point and means for breaking either of the toggles to quickly release a choke. 10
19. In a printing press folder, the combination with the folding cylinder and its blade, of a pair of folding rollers mounted in arms movable about a common axis external to the folding cylinder, means for variably positioning said rollers relative to each other and equidistant from the cylinder and the point of folding and means for quickly moving said rollers out of folding relation. 15
20. In a printing press folder, the combination with the folding cylinder and its blade, of a pair of folding rollers mounted in arms movable about a common axis external to the folding cylinder, means for yieldingly urging said rollers together and means for spacing said rollers from each other simultaneously and equidistant from the line of fold. 20
21. In a printing press folder, the combination with the folding cylinder and its blade, of a pair of folding rollers pivotally mounted for movement about an axis externally of the cylinder, a toggle yieldingly connected with each end of each roller and yieldingly pressing the rollers into folding relation, means for simultaneously moving the folding rollers equal distances from the line of folding, and means for quickly moving either roller away from the other and the cylinder and for returning the roller to its original position without disturbing the spacing of the rollers. 25
22. In a printing press folder, the combination with the folding cylinder and its blade, of a pair of folding rollers pivotally mounted for movement about an axis externally of the cylinder, a toggle yieldingly connected with each end of each roller and yieldingly pressing the rollers into folding relation, means for simultaneously moving the folding rollers equal distances from the line of folding, means for driving the folding rollers in any of their folding positions, and means for quickly moving either roller away from the other and the cylinder and for returning the roller to its original position without disturbing the spacing of the rollers. 30
23. A folding mechanism for a high speed rotary printing press including in combination a pair of parallel folding rollers, means for minutely and simultaneously moving the folding rollers to vary the folding gap between the rollers and means operable by a single movement to increase the folding gap to non-folding proportions to release a choked fold. 35
24. In a folding mechanism, the combination with a folding blade of a pair of folding rollers mounted in arms movable about a common axis 40
- on the opposite side of the rollers to the folding blade. 5
25. In a folding mechanism, the combination with a folding blade of a pair of folding rollers mounted in arms movable about a common axis, and means for yieldingly pressing said rollers together. 5
26. In a folding mechanism, the combination with a folding blade of a pair of folding rollers mounted in arms movable about a common axis, 10 and means for moving said arms apart to space the rollers from each other. 10
27. In a folding mechanism, the combination with a folding blade of a pair of folding rollers mounted in arms movable about a common axis, 15 and means for quickly moving said rollers from each other to release a choke. 15
28. In a folding mechanism, the combination with a folding blade of a pair of folding rollers mounted in arms movable about a common axis, 20 means for simultaneously spacing said arms apart to space the rollers from each other and the line of fold and means for quickly moving the rollers to release a choke without destroying the adjustment of the spacing means. 25
29. In a printing press folder the combination with the folding cylinder and its blade, of a pair of folding rollers, means for yieldingly pressing said folding rollers towards each other and into folding relation and means for releasing the yielding pressure to permit the rollers to move away from each other. 30
30. In a printing press folder, the combination with the folding cylinder and its blade, of a pair of folding rollers, means for yieldingly pressing said folding rollers towards each other and into folding relation and means for quickly releasing the yielding pressure on one of the folding rollers to release a choked fold. 35
31. In a printing press folder, the combination with the folding cylinder and its blade, of a pair of folding rollers, means for yieldingly pressing said folding rollers towards each other and into folding relation, means for quickly releasing the yielding pressure on one of the folding rollers to 40 release a choked fold and means for minutely varying the spacing of the folding rollers for folding products of varying thickness. 45
32. In a printing press folder, the combination with the folding cylinder, and its blade, of a pair of folding rollers, a pair of supports for the folding rollers at each end, said supports being pivoted to the frame about a common pivot so that the rollers can be swung toward or from each other independently. 50
33. In a printing press folder, the combination with the folding cylinder and its blade, of a pair of folding rollers, coaxially pivoted mountings therefor and means for independently moving either of said rollers. 55
34. In a printing press folder, the combination with the folding cylinder and its blade, of a pair of folding rollers, a pair of supports for the folding rollers at each end, said supports being pivoted to the frame, and means for independently moving either of said rollers and its supports about its pivot. 60
